CLAIM

The ornamental design for a display screen with graphical user interface as shown and described.

DESCRIPTION

The FIGURE is a front view for a display screen with graphical user interface showing our new design.

The cross-hatched area of the graphical user interface having forwardly slanted thinly spaced lines illustrates a contrasting appearance with the cross-hatched area of the graphical user interface having rearwardly slanted widely spaced lines. The peripheral dash-dot-dash lines illustrate a display screen or portion thereof and form no part of the claimed design. The dashed broken lines within the peripheral dash-dot dash lines illustrate portions of the graphical user interface, which form no part of the claimed design.
